UNITED STATES PATENT OFFICE.

JOSIAH VAVASSEUR, OF LONDON, ASSIGNOR TO W. G. ARMSTRONG, MITCHELL & CO., LIMITED, OF NEWCASTLE-UPON-TYNE, ENGLAND.

QUICK-FIRING GUN.

SPECIFICATION forming part of Letters Patent No. 451,864, dated May 5, 1891.

Application filed July 18, 1890. Serial No. 359,184. (No model.)

To all whom it may concern:

Be it known that I, JOSIAH VAVASSEUR, engineer, a subject of the Queen of Great Britain, residing at London Ordnance Works, 5 Bear Lane, Southwark, in the county of Surrey, England, have invented an Improved Mounting for a Quick-Firing Gun, of which the following is a specification.

The mounting is formed of a sole-plate or turn-table turning around a fixed central pin or pivot and supported around its circumference upon a horizontal ring of rollers. A flat upright armor-plate rises up from the sole-plate at right angles to the axis of the gun and a short distance in front of the pin or pivot. The armor-plate is supported in rear by two parallel upright brackets, which rise up from the sole-plate. A cradle in which the gun is carried lies between the brackets, and the trunnions of the cradle are supported in bearings, which the brackets carry. The men working the gun and the mechanism are protected by the armor-plate, and also by a cylindrical shield, which, excepting an opening in rear, nearly surrounds the gun. The armor-plate extends entirely across the cylindrical shield from side to side, and the shield is fixed to its ends. Immediately in rear of the armor-plate and between the upright brackets which support the armor-plate and the cylindrical shield is a sighting-station at one or both sides of the gun. The platform on which the man stands in the sighting station or stations is carried by the sole-plate or turn-table. The adjustment of the sight-bar and the training and elevating of the gun are done, as hereinafter described, by hand-wheels from this sighting station or stations. The gun projects through an embrasure cut through the armor-plate and also through another cut through the front of the cylindrical shield. The gun is carried as low down or near to the sole-plate as is practicable consistently with the gun being elevated to a considerable angle when necessary. This is of considerable importance in the case of guns of large size, and with this object the hydraulic and spring apparatus, by which the recoil is controlled and the gun returned to firing position, is carried upon the cradle above the gun in place of be-

low it or at the sides, as is usual. The recoil apparatus consists of a cylindrical casing parallel to the axis of the gun. The hydraulic cylinder occupies the rear end of the casing. 55 A piston works in the cylinder, and its rod passes out rearward from the cylinder and is fixed to an arm that projects upward from the gun. Within the front of the casing are springs. These at their rear end bear against 60 the front of the hydraulic cylinder and at the front bear against a plate, which by two horizontal rods is connected to the arm which projects up from the rear end of the gun. The passage of liquid from one end of the 65 hydraulic cylinder to the other is controlled in any ordinary manner.

The sighting is done through a vertical slot cut through the upper part of the armor-plate, so that the opening is high above the gun. 70 The front and back sights are both mounted upon a sight-bar, which is made to project outward through the slot, so that the back sight may be within or in close proximity to the slot and a large range of view obtained 75 with but a comparatively narrow slot. The sight-bar is mounted upon the top of the cradle in such a manner that it can be inclined to it to any desired extent. The roof over the portion of the cylindrical shield which is 80 in front of the armor-plate is below the sighting-opening, so that the range of vision is not obstructed by it.

In place of the central pivot the mounting may be arranged to turn about a front pivot; 85 but the central pivot arrangement is usually preferable, as it affords better protection to the men working the gun.

Figure 1 of the drawings annexed is a side elevation, partly in section, of the mounting. 90 Fig. 2 is a plan view of part of the same. Fig. 3 is a part back view. Fig. 4 is an elevation showing a modified way of carrying the sight-bar. Fig. 5 is a plan view of the same. Fig. 6 is a side elevation with part of the shield-swiveling sole-plate, together with the removed shield of the armor-plate, the vertical brackets, and the gearing carried by them. Fig. 7 is a vertical section of the same, showing also the central pin or pivot and the gearing for turning the sole-plate around this pivot. Fig. 8 is a plan view of the same with 95 100

- a portion of the upper part of the outer shield cut away. Fig. 9 is a cross-section to a larger scale through the line *a b*, Fig. 6. Fig. 10 is a plan, and Fig. 11 a side elevation, of the 5 cradle; Fig. 12, a plan; and Fig. 13 is a longitudinal vertical section of the same with the gun lying in it. Fig. 14 is a cross-section on the line *c d*, Fig. 10; and Fig. 15, a cross-section on the line *e f*.
- 10 A is a bed-plate, which is securely bolted to any deck. A central pin or pivot stands up from the bed-plate and around it is a circular roller-track, on which rests a ring of rollers B.
- 15 C is the sole-plate or turn-table resting on the rollers. The central pin or pivot rises up through the center of the sole-plate.
- 20 D are clips which prevent the sole-plate rising from the bed-plate.
- 25 E is the armor-plate, which stands up from the sole-plate.
- 20 F are the two vertical brackets which support it at the rear.
- 25 G is the cylindrical shield surrounding the mounting, except at the rear.
- 30 H is the gun, and I the cradle, in which it it can slide endwise.
- 35 I' are the trunnions of the cradle. They turn in bearings I'', carried by the brackets.
- 30 J is a cylindrical casing formed on the top of the cradle above the gun.
- 40 K is a hydraulic cylinder occupying the rear end of this casing.
- 45 K' is the piston-rod extending rearward and secured to an arm H', which stands upward from the rear end of the gun.
- 50 L are coiled springs within the front end of the casing J.
- 55 L' is a central support extending through the center of the coils of the springs.
- 60 L² is a plate which bears against the front end of the springs. A rod L⁴, extending from the support L, passes through a hole formed through the center of this plate, and a nut is 45 screwed onto the end of the rod. This prevents the springs from expanding too far and allows of their being taken out from the cylinder without permitting them to become un-compressed.
- 65 L⁵ is a plate bearing against the plate L². It has two lugs projecting from it which pass out through slots in the sides of the casing J from these lugs. When the recoil takes place, the plate is drawn back by the gun and the 55 springs are compressed. After the recoil the gun is moved forward again, as usual, by the springs. The running forward is preferably controlled, as has before been done and as is shown in Fig. 13, by a tapering spindle fixed 60 to the fore end of the hydraulic cylinder passing into the piston-rod, which is made hollow, and offering resistance to the free escape of liquid from the hollow of the piston-rod. To control the recoil, the piston has preferably a 65 notch cut from its circumference, and a rib fixed along the interior of the cylinder passes through the notch and by its form regulates

the size of opening left for liquid to pass from one end of the cylinder to the other at every part of the stroke. This way of controlling the recoil is well known.

M is the sight-bar carrying the front and rear sights used for aiming and giving the required elevation to the gun. It is made to slide into a dovetail groove formed along the 75 top of a slide M', so that it may be shifted backward or forward in the slide, as may be desired. The slide has a dovetail projection on its under side which enters a corresponding groove formed along the curved 80 top of the arm or projection M², which stands up from the top of the cradle, and in this way the sight-bar can be inclined to the cradle to any desired extent, and so any desired elevation can be given to the gun, as the longitudinal 85 axis of the gun is always concentric with the longitudinal axis of the cradle. When not in use, it can be drawn back along the dovetail groove in the slide M', so as not to project through the sighting-opening. When 90 in use, it is thrust forward until the rear sight comes within the opening. Movement can be given to the slide M' by a curved toothed rack upon it gearing into a pinion M³, which can be turned by a small hand-wheel M⁴ on its 95 axis.

N is the platform of the sighting-station on the left-hand side of the gun. The man standing on this platform can not only adjust and use the sights, but also train and give the required elevation to the gun.

The training is effected by turning the hand-wheel O, and the elevation is given by turning the hand-wheel P or P⁸. The axes of these wheels are carried in bearings by one 105 of the upright brackets F. The hand-wheel O is at the upper end of a vertical axis O', which at its lower end gives motion by bevel-wheels O² to a horizontal axis O³, (see Figs. 6 and 8,) which passes through the bracket and 110 on its inner end carries a worm O⁴, that gears with a worm-wheel O⁵, fixed, as usual, by a frictional connection or clutch of ordinary construction to the central pin or pivot which stands up from the bed-plate A. The hand-wheel P gives motion by bevel-wheels P' to an inclined axis P², on which is a worm P³, that gears into a worm-wheel P⁴, which by a friction-clip P⁵ is held fast to an axis P⁶, on which is a pinion P⁷, that gears into a curved 120 toothed rack, which is fixed to the gun-craddle I. The axis P² also carries a hand-wheel P⁸ on its rear end, so that elevation can be given to the gun either by turning the hand-wheel P or the hand-wheel P⁸.

In place of the sights being carried by a bar that can be slid backward or forward along a curved arm, as shown at Fig. 1, the bar may be carried by a block or tubular bearing that is jointed to an arm that stands out from the saddle, and may be set to any desired inclination by means of an arm extending rearward from the block, as shown in Figs. 4 and 5. In these figures M is the

sight-bar capable of being slid backward in a block or tubular bearing Q , jointed at Q' to an arm M^2 , which stands up from the cradle. Q^2 is an arm extending rearward from the bearing Q and carrying at its end a small pinion Q^3 to gear into a curved toothed rack Q^4 , fixed to the cradle or inner end of the projecting arm M^2 , so that by turning the pinion in one or other direction the sight-bar can be set at any desired inclination. When carrying the sight-bar in this way, the back sight may conveniently be on the bearing Q , and the front sight only on the bar. When not in use, the bar is slid back in the bearing Q , so as to be out of the way, or both sights may be on the bar and the whole arranged to slide back for removal from the bearing. The arm M^2 , which stands up from the cradle, can also be slid backward, so that when the sights on either side of the gun are not in use the sighting-aperture may be closed.

What I claim is—

1. In combination with a turn-table having an armor-plate rising up from and passing across it and having two parallel brackets supporting the armor-plate at the rear and a cylindrical shield extending around the gun,

except at the rear, and a gun-cradle lying between the brackets, with its trunnions supported in bearings carried by the brackets, a 30 sighting station or stations at the side or sides of the gun within the cylindrical shield and just in rear of the armor-plate, and training and elevating mechanism worked by hand-wheels from this sighting station or stations. 35

2. In combination with a turn-table having an armor-plate rising up from it, in which is a port-hole through which the gun projects, and with a gun carried within a cradle turning on trunnions just in rear of the armor-plate, a sight-bar carried by the cradle and projecting out through a separate sight-opening formed through the armor-plate, so that the back sight may be in close proximity to the sighting-opening. 40

3. The combination of the gun, the cradle in which it lies, and a sight-bar carried on the top part of the cradle and capable of being inclined to it to any desired extent. 45

JOSIAH VAVASSEUR.
